M. R. DUFFY

PAVEMENT LIGHT

Filed March 28, 1921

Miles R. Duffy
by George Curran. Atty.

UNITED STATES PATENT OFFICE.

MILES R. DUFFY, OF CHICAGO, ILLINOIS.

PAVEMENT LIGHT.

Application filed March 28, 1921. Serial No. 456,478.

To all whom it may concern:

Be it known that I, MILES R. DUFFY, a citizen of the United States, residing at Chicago, in the county of Cook and State of Illinois, have invented new and useful Improvements in Pavement Lights, of which the following is a specification.

This invention relates to vault and pavement lights.

10 Among the objects of my invention is to make these lights of a series of relatively small, readily handled units, each comprising a plurality of prisms, and to clamp the prisms between the frames 15 with yielding gaskets interposed between them so that a repair may be readily made by unclamping the frames and loosening the particular prism or prisms which are to be repaired. Furthermore, 20 the units being relatively small and easily handled, are connected in such a way to the supporting structure that the frames may be lifted out bodily when a repair is to be made, and the removed unit 25 replaced by a new one, the repairs being made in the shop, so that the sidewalk is at no time caused to be barricaded or interfered with while the repair is being made.

The invention consists further in the materials hereinafter described and more particularly pointed out in the appended claims.

In the accompanying drawings—

Fig. 1 is a fragmentary perspective view of a pavement or sidewalk provided with units constructed and arranged in accordance with my invention;

Fig. 2 is an enlarged, transverse, vertical sectional view taken through the units shown in Fig. 1;

Fig. 3 is a vertical sectional view showing a detail of construction;

Fig. 4 is a fragmentary top plan view of a portion of the upper frame of one of the units; and

Fig. 5 is a view showing the various elements which make a complete unit, disassembled but arranged in the positions in which they are put together.

In Fig. 1 of the drawings, 1 indicates a building wall rising above a sidewalk or

pavement at its inner edge, and in which pavement are units or frames 2 containing prisms or lights, in accordance with my invention, these units being located in the pavement between the building wall and the portion 3 of the pavement adjacent the curb.

The units 2 are all alike and of the same size, so a description of one will suffice for all. As clearly shown in Figs. 2 and 5, each unit 2 comprises a top frame 4 and a bottom frame 5, both being made of sheet or other metal and of the same size. The size of these frames is such that a single frame may be readily and conveniently handled by one workman. The frames 4 and 5 are provided with a like number of openings, which register or are in alignment when the frames are placed one above the other, and these openings are shaped to receive the prisms or lights 6 located between the frames, as shown in Fig. 2. Each prism 6 has an outwardly projecting rib 7 extending completely about it between its upper and lower ends, to form shoulders for the frames, and thus position the prisms between them. Between the ribs 7 and the frames 4 and 5 are gaskets 8 and 9. These gaskets have the same general shape as the frames and are provided with the same number of openings to receive the prisms. The gaskets 8 and 9 are made of resilient material, preferably rubber and are cut or formed from sheets of that material, and have portions engaging the ribs 7 and extending completely around the same.

To secure the frames together and thus hold between them the prisms 6 and the gaskets 8 and 9, I provide clamp bolts 10, one of which is shown in Fig. 3. The marginal and cross-members of each frame 4, 5 are made channel shape, as shown in the drawings, and the channels in the top frame 4 are filled with a composition such as lead or carborundum or other abrasive with a binder to make safety tread strips 11, as shown in the drawings, and thus provide safe walking under any weather condition. These safety strips 11 are substantially flush with the upper edges of the top frame 4, 100

and the ribs 7 on the prisms 6 are so positioned to make the prisms substantially flush with the upper edges of the frame.

Where each bolt 10 is located, the top frame 4 is provided with a key shaped slot 12, as shown in Fig. 4, to allow the head of the bolt 10 to pass through it when shifted to the enlarged end of the slot, and to prevent the bolt head from dropping through the slot when at the other or narrower end thereof, as shown by dotted lines in said figure. To prevent the tread strip 11 from adhering to the head of the bolt and thus hinder the ready and easy removal of it when necessary, I place over the bolt head a metal plate 13, which is of a size to fit in the channel and engage the side walls thereof to hold it from displacement when pouring or placing the composition of the tread strip 11 over the same. This plate 13 is curved or crowned to fit over the bolt head, as shown in Fig. 3. The bolt 10 projects downward through the lower frame 5 and there receives a nut 14 to clamp the frames together with the prisms and resilient gaskets between them. To unclamp the frames 4 and 5 to release the prisms 6 for repair or otherwise, the nuts 14 are removed from the bolts 10, the bottom frame 5 removes, and then the bolts shifted into the enlarged portions of the slots 12 and then withdrawn from them. The top frame 4 may then be removed without disturbing the tread strips 11. To clamp the parts together, they are assembled and secured together by the bolts, as is obvious. This enables broken, scratched or damaged prisms 6 to be readily and easily replaced, without being required to chip the prisms from the structure as required in the structures heretofore used.

The units are supported in place in the pavement in the following manner. To the building wall 1 is secured a structural steel member 15 having a forwardly projecting flange 16. When the distance between the pavement 3 and the building wall is such as to need more than one unit 2, there are provided intermediate supporting members 17 in the form of structural beams, as shown in Figs. 1 and 2, and having laterally projecting flanges 18, 18 on opposite sides thereof. The pavement 3 is formed with a ledge or shoulder 19. All parts of the units 2 are clamped together before being placed in the pavement, and when inserted in place rest on the flanges mentioned. To hold the units in place or down against the structural members, I provide a number of turnbuckles 20 having their upper ends somewhat hook-shaped to engage in apertures in depending flanges 21 on the bottom frame 5, and their lower ends hooked to engage under the supporting members, as shown in Fig. 2. To make a leak proof

joint between the bottom frame 5 of each unit 2 and its supporting members, I provide for each unit a rectangular gasket 22, which may be of lead. This extends around the associated unit, and is open to permit the prisms 6 and flanges 21 to project through the same. When the pavement has a number of units arranged lengthwise thereof, cross-beams 23 are provided to support the sides of the interposed units, as indicated in Fig. 1.

As shown and described herein, each unit 2 comprises a plurality of lights or prisms 6, and each unit is made in such a small size that it may be conveniently handled, lifted, and repaired by a single workman. Should any of the prisms or lights become damaged or broken by use in a pavement, it is not necessary to chip out the light or the cement binder about the same, as heretofore, or to barricade the pavement while the work is being done or while the cement sets and becomes hard after the repair has been made, thus blocking free movement of traffic over the pavement during all of that time.

With my invention, whenever any one or more of the prisms in any one or more of the units 2 become broken or damaged by use in the pavement, the particular unit or units, as the case may be, are readily and easily lifted out of the pavement after loosening the turn-buckles for that unit, and a new unit inserted in its place and clamped down, as is apparent. The use of the pavement is interfered with no longer than required to take out a unit and put another in its place, and this is a comparatively short time when compared with the time required for repairing as heretofore. The damaged unit after removal is taken to the shop and repaired as time permits. This saves time and labor in making repairs, which is quite an item in the upkeep and maintenance of payment lights in large cities where traffic over pavements is heavy and where pavement lights, in many cases, extend around a building the entire city block and then over practically all of the pavement from the building wall to nearly the curb line. This reduction in hindrance to traffic over the pavement when repairs are made, and the fact that the repairs may be made in the shop is a saving in the upkeep of the sidewalk, because, for one thing, the workman can make the repairs at times when he is not engaged in other work in and about the building. Moreover, the frames being separable and no cement or other binder being used to hold the prisms in place, makes repairs possible by unskilled labor, which is another saving in the cost of pavement maintenance.

The prisms 6 completely fill the openings in the top frame 4, and thus do not require

the use of a binder or cement to make the joint between such parts. Moreover, the resilient gaskets provide a sufficient joint between the prisms and the frames, and the 5 gaskets being of resilient material will yield under expansion and contraction of the parts and thus avoid the likelihood of breaking prisms through that factor. The units 2 may be made at the factory and 10 shipped completely assembled to the job and there laid, without requiring the making of any joints about the prisms or otherwise working on the units other than clamping them in place.

15 The use of relatively small units makes it possible to use relatively narrow marginal and cross strips in the frames, thus not only making the frames light in weight but giving more light per square foot of surface, as the 20 amount of glass may be increased over that as heretofore.

Other and further advantages incident to my invention will be apparent to those skilled in the art to which it relates.

25 While I have shown and described herein in detail a structure embodying the features of my invention, it is to be of course understood that the details of construction and arrangement of parts may be variously 30 changed and modified without departing from the spirit and scope of my invention. Furthermore the use of the word "prisms" in the specification and claims to denote the glass inserts 6 is to be comprehensive enough 35 to cover lenses or any other form of translucent inserts that may be used in the frames or units.

I claim as my invention:

1. A device of the character described, 40 comprising top and bottom frames, stamped from sheet metal and having aligned openings, prisms fitting in said openings, said prisms having outwardly projecting ribs between the top and bottom surfaces of said 45 prisms and extending completely about the same, said ribs being between said frames, sheet gaskets having substantially the same shape and size of said frames and arranged on opposite sides of said ribs between the 50 same and said frames, said gaskets having openings to receive said prisms and registering with the openings in said frames, and means for releasably clamping said frames together and against said ribs.

55 2. A device of the character described, comprising top and bottom frames, stamped from sheet metal and having aligned openings, prisms fitting in said openings, said prisms having outwardly projecting ribs 60 between the top and bottom surfaces of said prisms and extending completely about the same, said ribs being between said frames, sheet gaskets having substantially the same shape and size of said frames and arranged 65 on opposite sides of said ribs between the

same and said frames, said gaskets having openings to receive said prisms and registering with the openings in said frames, and bolts extending through said gaskets between said ribs and engaging said frames for releasably clamping the same together and against said ribs. 70

3. A device of the character described, 75 comprising top and bottom frames, stamped from sheet metal, and having marginal and cross members, forming aligned openings in said frames, prisms fitting in said openings and having ribs between said frames, gaskets between said ribs and frames, means for releasably clamping said frames together, and 80 safety tread strips carried by the marginal and cross-members of said top frame.

4. A device of the character described, 85 comprising top and bottom frames, stamped from sheet metal, and having marginal and cross members, forming aligned openings in said frames, prisms fitting in said openings and having ribs between said frames, gaskets between said ribs and frames, means for releasably clamping said frames together, the 90 marginal and cross members of said top frame being channel shaped, and safety tread strips in said channels.

5. A device of the character described, 95 comprising top and bottom frames, stamped from sheet metal, and having marginal and cross members, forming aligned openings in said frames, prisms fitting in said openings and having ribs between said frames, sheet gaskets on opposite sides of said ribs and having openings to receive said prisms and registering with the openings in said frames, the marginal and cross members of said top frame being channel shaped, and certain of 100 said members having key shaped holes therein, bolts extending through said holes and said bottom frame for clamping the frames together, safety tread strips molded in said channels, and plates below said tread strips and over said bolt heads for 110 covering the same.

6. In a pavement, the combination with an open framework constituting a supporting structure for pavement lights, of a plurality of units, all of substantially the same size and capable of being easily and readily handled, each unit comprising top and bottom metal frames with prisms between them, means in each unit for detachably clamping the frames together and holding the prisms between them, and means located beneath 115 said units for detachably clamping the same separately to said supporting structure, said last named means being accessible from beneath said units. 120

7. In a pavement, the combination with an open framework constituting a supporting structure for pavement lights, of a plurality of units, all of substantially the same size and capable of being easily and readily 130

handled, each unit comprising top and bottom metal frames with prisms between them, means in each unit for detachably clamping the frames together and holding the prisms between them, and means located beneath said units for detachably clamping the same separately to said supporting structure, said last named means being engaged with the

bottom frames of the several units and the supporting structure and accessible from beneath the latter. 10

In testimony that I claim the foregoing as my invention, I affix my signature this 26th day of March, A. D. 1921.

MILES R. DUFFY.
